OIL-ENGINE.

1,159,341.

Specification of Letters Patent.

Patented Nov. 2, 1915.

Application filed November 16, 1914. Serial No. 872,290.

To all whom it may concern:

Be it known that we, FRANKLIN G. HOBART and CHARLES B. JAHNKE, citizens of the United States, residing at Beloit, in the 5 county of Rock and State of Wisconsin, have invented a certain new and useful Improvement in Oil-Engines, of which the following is a specification.

This invention relates to explosive engines 10 in which oil is used as a fuel, and particularly to that class of engines of this sort in which an approximately spherical or a more or less egg shaped combustion space is provided at the compression end of the cylinder 15 connected thereto by a passageway for the movement of gas, some part of the wall of said combustion chamber being in the first instance heated by external means, as a blow torch, after which the heat of said wall ignites the oil as it is sprayed into the chamber. 20

The object of the invention is to provide a device of this class which is capable of operation without spray-water, which is relatively inexpensive to build, which is more efficient than devices heretofore known and used, which is very sure and accurate in its operation and not readily liable to get out of order. 25

30 The invention consists in a device capable of carrying out the foregoing objects, and more particularly in the features of construction which will hereafter be more fully set forth in the specification and claims.

35 Referring to the drawings, in which similar numerals indicate the same parts throughout the several views, Figure 1 is a sectional detail view through a device illustrating this invention in its preferred form. 40 Fig. 2 is an end view partially in section taken on the line 2-2 of Fig. 1. Fig. 3 is a view corresponding to Fig. 1, showing a modified form of the device. Fig. 4 shows an alternative construction for the interior 45 of the combustion chamber.

The preferred form of the device, illustrated in Fig. 1, comprises a cylinder 10 within which at the left of the figure is a piston, not shown, adapted to reciprocate. 50 The cylinder is closed by a head 12 having a central perforation 14 leading into a hot cap 16 secured in place by any suitable means, such for instance as the cover 18 through whose flange 20 the bolts 22 pass 55 into the cylinder head 12. The outer end of

the cylinder 12 and the inner surface of the cap 16 is hollowed out to form the elongated spherical or egg shaped combustion chamber 20.

The cylinder head 12 is preferably provided with a water jacket space 22 communicating with the main cylindrical water jacket 24. The hot cap 16 is also provided with its own independent water jacket space 26 adapted to receive and discharge water through suitable ports 30 provided for the purpose in the exterior wall of the water jacket at any convenient point, as shown in Fig. 2. The location of these ports and the method of getting the water to and from them is entirely immaterial. This water jacket 26 is separate and independent from the main water jacket system of the device so that water may be circulated through it when desired, as for instance when the engine is working continuously under a heavy load, or the water may be entirely omitted when desired, as for instance when the engine is working under a very light load or in a very cold place so that the use of the water jacket is unnecessary or even a detriment. 75

On the inside of the hot cap 16 and preferably located on the central axis of the engine cylinder, is a tubular cup 32 which may, however, take other forms without departing from this invention. In the preferred form the cup is open to the combustion chamber so as to receive some of the oil, and it improves the operation at light loads probably by starting ignition more promptly. 90

Extending through the cylinder head 12 is an oil nozzle 34 of any suitable construction known in the art connected at its outer end to any suitable source of oil supply and at its inner end adapted to direct a stream 36 of oil into the igniter cap 32, heretofore described. In proximity to the tube 32, heretofore described, is another tube 38 open at its inner end 40 into the combustion chamber 20 and having its outer end 42 closed. When starting the engine, this tube is heated by any suitable means, such for instance as a blow torch, and this small highly heated tube therefore serves as a temporary vaporizer and igniter of the stream 36 of oil coming in proximity to it until such time as the combustion chamber 20 becomes hot enough from the regular explosions. 105

Extending circumferentially of the com- 110

bustion chamber 20 at about its middle is an annular ring 44 having a flange 46 pointed toward the hot cap 16, the same being adapted to receive and check currents of combustible gas passing along the interior surface of the combustion chamber to the left, as viewed in Fig. 1, which, if unchecked, would create a suction drawing the oil spray away from the tube 32 where it should strike 10 in order to be properly ignited, improper ignition of the oil spray of course resulting in irregular operation of the engine. This ring 44 may be made integral with the interior of the cap or otherwise attached thereto 15 without departing from this invention. A similar but less effective result is obtained by providing on the interior of the hot cap 16 a plurality of inwardly projecting pins or plugs 48, as shown in the alternative construction of Fig. 3, and also by projecting wings or fins 60 cast integral with the hot cap as in Fig. 4.

In the operation of the device, assuming that the engine is cold, heat is first applied 15 to the tube 38 by a torch or the like, and after it has become thoroughly heated the oil spray 36 is started. As soon as some of this oil strikes a portion of the hot cap which this tube 38 has heated, the mixture is 20 ignited and, the resulting pressure in the combustion chamber 20 communicates through passageway 14 and drives the piston in the cylinder 10 to the left. In the meantime a supply of oil 36 has, by mechanism forming no part of this invention, been 25 shut off. As the engine piston completes its return stroke, this oil is again admitted into the compressed air, which now occupies the combustion chamber 20 and the operation is 30 repeated. When the closed end of the combustion chamber 20 has acquired sufficient heat from the operation of the engine to ignite successive charges of oil delivered by spray 36, the use of the blow torch is omitted 35 and the device works automatically in a manner well known in the art. Water is supplied to the water jacket space 26 or not, as the conditions under which the engine is 40 working may require in the manner and for 45 the reasons heretofore set forth, while the internal flange 44-46 insures the proper delivery of the oil spray 36 into the cup 32. The parts being proportioned as described, 50 highly efficient operation is obtained.

55 In the modified structure of Fig. 3, pins 48 or equivalent ribs 60 perform the function of the ring 44-46, the device of this structure operating the same as the device of Fig. 1.

60 Having thus described our invention, what we claim as new and desire to secure by Letters Patent is:—

65 1. In a device of the class described, a combustion chamber having an opening in one portion adapted to be connected to an

engine cylinder, a portion opposite said opening adapted to be maintained hot for the purpose of igniting fuel in the combustion chamber, means for directing fuel material against the hot portion of said combustion chamber, and gas obstructing devices inside said chamber between said opening and said hot portion for the purposes set forth. 70

2. In a device of the class described, a combustion chamber having an opening in one portion adapted to be connected to an engine cylinder, a portion opposite said opening adapted to be maintained hot for the purpose of igniting fuel in the combustion chamber, means for directing fuel material against the hot portion of said combustion chamber, and projections extending from the inside of the combustion chamber intermediate between said opening and said hot portion adapted to check the passage of air or gas traveling along the interior surface of the combustion chamber toward said opening. 80

3. In a device of the class described, a combustion chamber having an opening in one portion adapted to be connected to an engine cylinder, a portion opposite said opening adapted to be maintained hot for the purpose of igniting fuel in the combustion chamber, means for directing fuel material against the hot portion of said combustion chamber, and a circumferential ring on the interior of said chamber for impeding the passage of gas from the hot portion 90 of said chamber to said opening. 95

4. In a device of the class described, a combustion chamber having an opening in one portion adapted to be connected to an engine cylinder, a portion opposite said opening adapted to be maintained hot for the purpose of igniting fuel in the combustion chamber, means for directing fuel material against the hot portion of said combustion chamber, and a circumferential ring 100 on the interior of said chamber for impeding the passage of gas from the hot portion 105 of said chamber to said opening. 110

5. In a device of the class described, the combination of a combustion chamber having an opening in one portion, a heated portion opposite it, means for directing fuel into the combustion chamber toward said heated portion, devices inside said chamber for retarding the passage of gas from said heated portion toward said opening, and a water jacket around the combustion chamber 115 for regulating the temperature thereof. 120

6. In the art described, an engine combustion chamber having a portion adapted to be heated for igniting fuel therein, a fuel nozzle entering the chamber and directed toward said hot portion, and a projection on said 125 130

heated portion opening into the chamber and adapted to receive the stream of fuel from said nozzle, this in combination with devices inside the combustion chamber obstructing the flow of gas from the hot portion of the chamber toward its opposite end.

7. In the art described, an engine combustion chamber having a portion adapted to be heated for igniting fuel therein, a fuel nozzle entering the chamber and directed toward said hot portion, a cup in said heated portion opening into the chamber and adapted to receive the stream of fuel from said nozzle, this in combination with devices inside the combustion chamber obstructing the flow of gas from the hot portion of the chamber toward its opposite end.

8. In a device of the class described in combination with an engine cylinder, a combustion chamber connected to the end thereof and having a heatable portion opposite to its connection to the engine cylinder, a cup in the heatable portion of the combustion chamber having its open end entering the combustion chamber, a nozzle pointed into the combustion chamber adapted to direct fuel into said cup, retarding devices inside the combustion chamber and adjacent to its inner circumference adapted to impede the passage of gas from said heatable cup toward the entrance to the engine cylinder, and a device for regulating the temperature of the circumference of the combustion chamber, all of the parts being shaped, arranged and disposed as shown and described for the purposes set forth.

9. In a device of the class described, the combination of a combustion chamber, a fuel nozzle inside the chamber directing fuel against an opposite wall thereof, a cup in the last mentioned wall of the chamber adapted to receive the fuel from said nozzle, and an additional cup in immediate proximity to the first mentioned cup opening into the chamber and having its closed end extending outside the wall of the chamber so that external heat may be applied thereto, for the purposes set forth.

10. In a device of the class described, the combination of a combustion chamber, a fuel nozzle inside the chamber directing fuel against an opposite wall thereof, a cup in the last mentioned wall of the chamber adapted to receive the fuel from said nozzle, and an additional cup in immediate proximity to the first mentioned cup opening into the chamber and having its closed end extending outside the wall of the chamber so that external heat may be applied thereto, this in combination with a water jacket device for regulating the temperature of the external wall of the combustion chamber for the purposes set forth.

In witness whereof we have hereunto subscribed our names in the presence of two witnesses.
